UNITED STATES PATENT OFFICE.

GEORGE E. CHAMBERLAIN, OF ST. LOUIS, MISSOURI.

DRIER.

No. 822,185.

Specification of Letters Patent.

Patented May 29, 1906.

Application filed September 15, 1905. Serial No. 278,557.

To all whom it may concern:

Be it known that I, GEORGE E. CHAMBERLAIN, a citizen of the United States, and a resident of the city of St. Louis and State of Missouri, have invented a new and useful Improvement in Driers, of which the following is a specification.

My invention relates to driers, and has for its principal objects to prevent the choking up of the draft-flue, to clean out the draft-flue without interfering with the operation of the drier, to provide a readily-removable conveyer in the bottom of the draft-flue, and other objects hereinafter more fully appearing.

My invention consists in the parts and in the arrangements and combinations of parts hereinafter described and claimed.

In the accompanying drawings, forming a part of this specification, and wherein like symbols refer to like parts wherever they occur, Figure 1 is an end view of a drier equipped with my improvement. Fig. 2 is a vertical sectional view through the draft-flue 25 and the adjacent end of the drier-cylinder.

In drying disintegrated materials in driers traversed by a strong draft light or fine particles are carried by the draft to the flue and fall to the bottom thereof in such quantities as to choke it up in a short time. Hitherto it has been necessary to open a manhole in the flue and clean it out by hand. This interferes with the draft and the operation of the drier and results in the discharge of some insufficiently-dried material from the drier. If the operator attempts to regulate the feed during the time the manhole is open, it invariably follows that some overdrained material will be discharged from the drier, 35 because of the impossibility of instantaneously changing the feed. My improvement keeps the flue always open, obviates the necessity of opening the manhole to clean out the flue, and obviates the consequent inequality in the results produced.

In the machine illustrated the drying-chamber is a rotary cylinder 1. The drier-cylinder 1, provided with peripheral bearing-rings 2, rests upon rollers 3. A gear-wheel 4 on a power-shaft 5 engages a peripheral rack 6 on the cylinder and rotates the cylinder. The cylinder is internally heated by steam-pipes 7. The head 8 of the cylinder is provided with an annular bearing-plate 9, which bears against a pivotally-mounted bearing-plate 10.

The bearing-plate 10 has an opening near one side to receive a trough and screw conveyer 11, to which the material to be dried is fed by a chute 12. The conveyer 11 is actuated by the power-shaft 5 through sprocket-and-chain gearing and delivers the material to be dried to the drier-cylinder at one side of and below the major portion of the draft-flue opening, so as to avoid the draft as much as possible.

The bearing-plate 10 has a flue-opening at its upper portion surrounded by a flange 13. A draft-flue 14 is connected to said flange 13. The lower front portion 15 of said flue is shaped to form a trough for a screw conveyer. The lower rear portion 16 is box-shaped and has a manhole in the bottom, closed by a door 17. A flue-cleaning screw 18 is mounted in the lower part of the flue in the trough-shaped portion 15 and extends through the box-shaped portion 16. The flue-cleaning screw may be inserted and withdrawn through a hole 19 in the rear side of the flue. It is journaled in a swinging bearing 20, pivoted upon the upper side of the flue, and in a stuffing-box 21, which is integral with a plate 22, which closes the hole 19. The plate 22 is secured to the flue by studs and nuts and is thus readily removable to permit access to the interior of the flue through the manhole should it ever become necessary. The swinging bearing will align with the fixed bearing. The conveyer-screw 18 is geared to the screw of the feeding-conveyer by means of sprockets and chains. Hence whenever the conveyer 11 is actuated to feed material into the drier-cylinder the flue-cleaning conveyer will be actuated to keep the flue from choking up. An apron 23 is mounted on the bearing-plate 10 and extends over the bearing-plate 9 to prevent the falling between said bearing-plates of material discharged by the flue-cleaning screw.

The drier being set in operation, the drier-cylinder will be rotated and the feed-conveyer and flue-cleaning screw will be actuated. Material carried by the draft into the flue and falling there will fall upon the flue-cleaning screw and will be carried back into the cylinder. There it will fall down and mingle with wet goods delivered by the feed-conveyer and will be carried along with the same to be discharged at the opposite end of the conveyer. The flue-cleaning screw being in continuous operation, the material falling to the bottom of the flue will be carried back

into the cylinder as fast as it falls, and thus the flue can never choke up.

Obviously my device is capable of modification within the scope of my invention, and therefore I do not wish to be limited to the particular construction shown and described.

What I claim as my invention, and desire to secure by Letters Patent, is—

1. A drier comprising a drying-chamber, a flue communicating with said chamber, a feeding-conveyer and a flue-cleaning conveyer arranged in the lower portion of said flue.

2. A drier comprising a drying-chamber, a flue communicating with the same, means for feeding said chamber, and a flue-cleaning conveyer removably mounted in the bottom of said flue.

3. A drier comprising a drying-chamber and means for feeding the same, a flue communicating with said chamber and having a trough-shaped lower portion, and a rotatable screw mounted in said trough-shaped portion of said flue.

4. A drier comprising a rotary cylinder and means for feeding the same, a flue communicating with said cylinder, and a flue-cleaning conveyer arranged in the bottom of said flue.

5. A drier comprising a rotary cylinder, a flue communicating with said cylinder, a con-

veyer for feeding said cylinder and a flue-cleaning conveyer arranged in the bottom of said flue to carry material into said cylinder, and an apron arranged beneath the discharge end of said conveyer.

35

6. A drier comprising a draft-flue, a rotary cylinder opening into said draft-flue, a feed-conveyer arranged to deliver material into said cylinder to one side of the opening into said draft-flue, and a flue-cleaning conveyer arranged in the bottom of said draft-flue to deliver material into said cylinder in position to mingle with the material delivered by said feed-conveyer.

40

7. A drier comprising a rotary cylinder, a flue communicating with said cylinder, a feed-conveyer arranged to deliver material to be dried into said cylinder, a flue-cleaning conveyer arranged in the bottom of said flue, means to actuate said rotary cylinder, and gearing connecting said means and said conveyer, whereby said cylinder and said conveyer will always be simultaneously actuated.

45

Signed at St. Louis, Missouri, this 13th day of September, 1905.

GEO. E. CHAMBERLAIN.
